TRANSMISSION HOUSING FOR CENTRIFUGAL PUMPS

Harry J. Sadler, Minneapolis, Minn., assignor to Hypro Engineering, Inc., Minneapolis, Minn., a corporation of Minnesota

Filed Oct. 29, 1962, Ser. No. 72,290

Term of patent 14 years

(Cl. D65—1)

FIG. 1

FIG. 2

FIG. 3

FIG. 4

FIG. 5

FIG. 6

FIG. 1 is a view in front elevation of a transmission housing for centrifugal pumps, showing my new design; FIG. 2 is a view in rear elevation thereof;

FIG. 3 is a view in side elevation thereof as seen from the left of FIG. 2;

FIG. 4 is a view in side elevation thereof as seen from the right of FIG. 2;

FIG. 5 is a view in bottom plan thereof; and

FIG. 6 is a view in top plan thereof.

The dominant features of my design reside in the portions shown in full lines.

I claim:

The ornamental design for a transmission housing for centrifugal pumps, as shown and described.
